UNITED STATES PATENT OFFICE.

JOHN LOCKE, OF LEWISBURG, AND JOHN CLARK, OF MILROY, PENNSYLVANIA.

IMPROVEMENT IN HUBS FOR CARRIAGE-WHEELS.

Specification forming part of Letters Patent No. 131,887, dated October 1, 1872.

To all whom it may concern:

Be it known that we, JOHN LOCKE, of Lewisburg, in the county of Union and State of Pennsylvania, and JOHN CLARK, of Milroy, in the county of Mifflin and State of Pennsylvania, have invented a new and valuable Improvement in Wheel-Hubs; and we do hereby declare that the following is a full, clear, and exact description of the construction and operation of the same, reference being had to the annexed drawing making a part of this specification, and to the letters and figures of reference marked thereon.

Figure 1 of the drawing is a representation of a front view, showing the modifications of my invention; Fig. 2 is a longitudinal central sectional view of the same. Fig. 3 is the same.

This invention has relation to metallic hubs for wheels; and it consists in the construction and novel arrangement of the sections composing the hub; in the form of the fastening-lugs, and their relation to the ends and shoulders of the spokes.

The accompanying drawing illustrates this invention as follows: The letter A designates the box, on which is cast the disk or flanch B. C represents the exterior disk or outer section of the hub, provided with a sleeve, a, and the dovetail lugs b, arranged in a circular series on the inside wall of the disk next the periphery thereof. These lugs are dovetail in form, as shown in Figure 1—the larger ends being toward the center. E represents the nut, which is screwed on the box and serves to keep the disks securely together. F designates the spindle of the axle, G the cap, and H the spokes. Each spoke is formed with a wedge-shaped end, c—the bevel of the sides of this end being regulated by the number of spokes in the wheel; these ends c being designed to fit closely together around the sleeve a. Each spoke is notched on both sides to receive the two dovetail lugs which are adjacent thereto. The notch c has two sides, meeting at an angle. One of these sides, m, is at right angles, or thereabout, with the direction of the spoke, forming a secure shoulder,

which will prevent the spoke from drawing out. The other side, n, is beveled obliquely outward and forward to fit closely the inclined side of the lug which forms its bearing. It is apparent that the expanded shoulder z of the spoke renders it strong at the junction with the hub. This formation is rendered possible by the form of the lug. Between the lugs and the sleeve a the space is filled with the closely fitting ends of the spokes, forming a compact ring of wood. Sometimes the lugs, instead of being attached to the outer disk, may be cast on the box-disk; but the arrangement first described is preferred, because the box can be easily replaced when worn out without disturbing the spokes in their bearings. The lubricating-recesses v v are indicated in Fig. 3 of the drawing. These recesses or shallow cells are arranged in the length of the wall of the box in such a way that the cells alternate with the wall s of the box in a checkered manner, as illustrated, so that the bearing of the box on its spindle shall be uniform throughout its length. Between each cylindrical arrangement of recesses the wall of the box is entire for a short distance, as at s', forming rings or bearings at different points, fitting the spindle closely. A great quantity of lubricating matter can be contained in these cells, and the friction of the box will be decreased by the lessening of the bearing-surface, the arrangement being such as to preserve the bearing uniform.

What I claim as my invention, and desire to secure by Letters Patent, is—

The combination, with the notched spokes, of the wheel-hub, made in two sections or disks, one of which is provided with the series of peripheral dovetail lugs, having their large ends lying inward, substantially as specified.

In testimony that we claim the above we have hereunto subscribed our names in the presence of two witnesses.

JOHN LOCKE.
JOHN CLARK.
